UNITED STATES PATENT OFFICE.

JACOB MEHRLUST, OF NEW YORK, N. Y.

FINGER-RING.

1,099,810.

Specification of Letters Patent.

Patented June 9, 1914.

Specification filed November 1, 1912. Serial No. 729,090.

To all whom it may concern:

Be it known that I, JACOB MEHRLUST, a citizen of the United States, residing at New York, in the county of New York and State of New York, have invented certain new and useful Improvements in Finger-Rings; and I do hereby declare the following to be a full, clear, and exact description of the invention, such as will enable others skilled in the art to which it appertains to make and use the same.

This invention relates to jewelry and more particularly to finger rings but may be used in the construction of bracelets as well.

15 An object of this invention is to provide a finger ring or the like which contracts so as to assure a perfect fit when properly applied but which is expansible to permit its passage over enlargements such as joints 20 or the like.

A further object of this invention is to provide a jointed ring which automatically contracts after passing an enlargement.

A further object of this invention is to 25 provide a finger ring or the like made up of sections, said sections having loose connections with each other and a resilient means passing through said sections to return them into bearing relation with one 30 another when said ring or the like has been properly placed.

Further objects will be apparent from the following specification, appended claim and drawings, in which—

35 Figure 1 is a side elevation of the device showing one half in closed position while the other half is shown in extended position, Fig. 2 is a sectional view of a section of the ring or the like showing the links in both 40 closed and extended position, Fig. 3 is a perspective view of one of the sections showing the lug extending therefrom, Fig. 4 is a similar view showing the section turned as to expose the opposite end, Fig. 5 is a 45 view of one of the springs, and, Fig. 6 is a transverse sectional view through the ring.

In the construction of finger rings the ability to expand a ring to permit its passage over a joint and its contraction when

properly placed will be appreciated by 50 many. Not only is it necessary to provide an expansible ring but means are necessary to normally contract the ring when in place. I provide that a ring may be made in a plurality of sections 10 which are provided on 55 their inner faces with ribs 11 which are drilled as at 12 to be hereinafter described. Each of the sections 10 is provided with a tongue 13 slotted as at 14, and this tongue is intended to slide between the ribs 11 of the 60 adjacent section.

A pin 15 passes through an opening 16 in each of the ribs 11, and through the elongated slot 14 of the tongue between the ribs. As each link is added, the section of the pin 65 15 traversing the opening 12 is removed in each link except in the last one applied, and, before the application of this last pin, springs 17 are inserted in the passages 12 of the several links.

The springs 17 pass through the passages 12 of each section and tend to hold the several sections in bearing relation with each other and these springs will yield when the ring is desired to be expanded by permitting 75 the several sections to slide thereon. Fig. 5 of the drawing shows the spring in released position in full lines and the dotted lines show the position it assumes when made up in a ring in its contracted form. 80 After the springs 17 are inserted, the exposed slotted tongue is placed between the exposed ribs of the link opposite thereto, where a pin 15 is inserted as usual. This pin remains in perfect condition.

85 Various modifications may be made within the scope of this invention without departing from the spirit of the invention and I do not restrict myself to the identical form shown which is submitted for illustrative 90 purposes only and

Having thus described my invention, I claim:

An expansible ring comprising a plurality of sections, each of said sections having a slotted tongue extending from one end thereof, each of said sections having ribs formed on one side thereof, said ribs having

passages therethrough, said ribs forming a recess to receive the slotted tongue of an adjacent section, said ribs having a transverse recess therethrough, a fastening means in the transverse recesses to engage the slotted tongue of the adjacent section, and springs passing through the passages in said ribs, said springs retaining the fastening

means for the several sections against displacement.

In testimony whereof I affix my signature in presence of two witnesses.

JACOB MEHRLUST.
